ARTICULATED VENETIAN BLIND TAPE

Ernest E. Wolfe, West Los Angeles, and Anthony G. Schuck, Los Angeles, Calif., assignors to Schuck Manufacturing Co., Inc., Los Angeles, Calif., a corporation of California

Application January 2, 1952, Serial No. 264,468

14 Claims. (Cl. 160—173)

1

This invention relates to Venetian blind tape of the type disclosed in the application of Ernest E. Wolfe, Serial No. 73,623, filed January 29, 1949, now Patent No. 2,601,896.

The general object of this invention is to provide improvements in articulated tape of the type disclosed in that application, in which hinge pintles are formed as thin, flat portions of the links themselves, and in which there is considerable resulting looseness in the hinges.

In the fabricating of Venetian blind tape from a series of stamped sheet metal links, hingedly joined by loops integrally formed at one end of each link and looped through slots in the adjacent end of an adjoining link, considerable difficulty has been encountered in the form of several specific problems. One of these is the problem of providing definitely for the breaking of one series of alternate hinges outwardly and the breaking of the intervening series of hinges inwardly, as the ladder is collapsed by moving its lower end upwardly toward its suspended upper end. Where fairly tight hinges are employed this may readily be accomplished by the provision of a finger or fingers on one link projecting past each hinge into engagement with an adjacent link in such a manner as to restrain breaking of the hinge in the wrong direction, but where a loose hinge of the type referred to above, is employed, the problem is more difficult.

One of the specific objects of the present invention is to provide a ladder having improved hinge loops cooperating with stop fingers utilized only on alternate tape links, in a construction and arrangement which is such as to render it possible to employ the loose type hinge structure, above referred to, and to obtain a more reliable pre-breaking of the hinges. The expedients of the prior art, for this general purpose, have not proved fully satisfactory for the purpose. Another problem that has been encountered is that of having the hinge loops open up under the tension applied to them. This problem is particularly aggravated in the hinges of the upper links of the ladder, which support the entire weight of the extended portion of the Venetian blind therebelow.

The present invention relates primarily to the shape of the hinge loops, and has as its object to provide Venetian blind ladder structure of the type indicated, having improved hinge loop structure so constructed and related to the links of the ladder structure and their arrangement with relation to each other, as to: (a) cause the alternating links of the ladder, when hanging

2

freely under the influence of gravity, to assume positions of slight inclination in opposite directions, with the respective hinges slightly broken in the direction in which they are intended to fold; and (b) effectively resist the tendency of the hinge loops to open up under normal tension applied to them, even in the uppermost hinge loops.

Other objects will become apparent in the ensuing specifications and appended drawings in which:

Fig. 1 is an inner side view of a portion of a Venetian blind articulated tape;

Fig. 2 is an edge view thereof, viewed from the left side of Fig. 1;

Fig. 3 is a fragmentary enlarged detailed sectional view through two adjacent hinges of the ladder;

Fig. 4 is a transverse vertical sectional view through a portion of a Venetian blind embodying the invention with the articulated ladder structure shown in edge elevation; and

Fig. 5 is a fragmentary outer side view of the ladder structure.

Referring now to the drawings in detail, our improved ladder structure comprises a pair of opposed articulated tapes (Fig. 4), each comprising a plurality of tape links A and A' hinged together, end to end, the opposed tapes being joined by a series of cross links B. The tape links A, A' are arranged with the links A constituting one series of alternate links and the links A' constituting an intervening series of links disposed alternately between the links A. The hinged connections between the links A and A' comprise a series of alternate, outwardly breaking hinges C and a series of intervening, inwardly breaking hinges C'. Cross links B are linked to the respective tapes at the hinges C, whereby hinges C' may fold inwardly between the slats of the collapsed blind structure, as indicated in Fig. 4.

Each tape link A comprises a rectangular body 9 of fairly rigid formable sheet material (such as sheet metal) having at one end thereof a pair of laterally spaced, sleeve-like hinge loops 10 and having at its opposite end a pair of laterally spaced ears 14 provided with respective aligned slots 13 which define, at the end extremities of said ears 14, a respective pair of aligned hinge pintles 15. Ears 14 project endwise from body portion 9 and define between them a central notch 16.

Each tape link A' comprises a rectangular body 9' of similar sheet material, having at one

end a pair of laterally spaced, sleeve-like hinge loops 10' linked through slots 13 and encircling pintles 15 to constitute hinges C; having at the same end a central loop 11, centered between and axially aligned with loop 10', received in notch 16 of link A, and spaced inwardly from the inner ends of loops 10' to define spaces 12 for receiving parts of the cross links B'; and having at its opposite end a pair of aligned transverse slots 13' in said opposite end. Hinge loops 10 of links A are linked through slots 13' and encircle pintles 15' to constitute hinges C'.

Hinges C are substantially concealed by lips 17' which are formed as integral extensions of those portions of hinge loops 10' which immediately adjoin body portions 9' of link A'. Similarly, each link A has a lip 17 constituting an integral continuation of those portions of loops 10 which immediately adjoin body portion 9 of link A.

Each cross link B includes a central body portion 18, for supporting a respective blind slat 19 (Fig. 4), a transverse trunnion portion 20 at each end thereof, and a return bent end portion or finger 21 which is disposed in a common plane with the body portion 18. Each trunnion portion 20 extends through a respective central loop 11, and end finger 21 cooperates with body portion 18 to embrace the ends of central loop 11 and prevent any lateral displacement of the cross link B relative to the tape structure. As indicated in Fig. 1, alternate links B have their body portions 18 thereof disposed on opposite sides of the median plane of the ladder structure. Thus the cross links B may be utilized as guides for confining a conventional blind operating cord 35 (Fig. 4).

End fingers 21 and opposed body portions 18 of the cross links B, are accommodated in spaces 12 between loops 10' and 11.

The ladder structure as defined above is largely the same as that disclosed in our above mentioned co-pending application. The present invention provides an improved form of hinge loop structure which is illustrated in detail in Fig. 3, and will now be described.

Each of the hinge loops 10, 10', includes a portion of the length of lip 17 (or 17') as an integral part thereof. Each of the lips 17, 17' includes two sections 22, 23 respectively, defining between them a dihedral angle (which may approach 90°) and joined by a bend 24. In the outwardly breaking hinge C, in which hinge loops 10' face inwardly, lip section 22 extends outwardly at an obtuse angle from the body portion 9 (or 9') to which it is immediately joined by a bend 27. Lip section 23 is inclined inwardly and across the plane of body portion 9', at an acute angle. To the end edge of section 23, the separated portions of loops 10 (or 10') are joined by bends. These separated portions of the loops are of roughly U or V section, each including at one side an arcuate arm 26 integrally joined to bend 25, and at its opposite side an arm 28 having a free end which engages section 22 of lip 17 (or 17'). Arms 26, 28 are joined by a bend 29.

The bends 25 function as stirrups in which trunnions 15 (or 15') are fulcrumed and positioned for pivotal movement during the initial stage of folding of the ladder. Such positioning 70 confines the downward pull of trunnions 15, 15' to lines of contact closely adjacent the free edges of lip sections 23. The end arms 28 of the loops are tucked against the inner walls of lip sections 22, in frictional engagement therewith such as to 75

resist, with an adequate safety factor, any tendency of the loops to open up. The lever arm 7 represented by the distance from bends 25 to the area of engagement between arms 28 and lip section 22 being many times greater than the lever arm 7' represented by the outermost line of engagement between a trunnion 15 (or 15') and the line where the loops adjoin continuous lip section 23, it will be apparent that the downward force exerted by a trunnion against the bend 25 by which it is supported may be correspondingly many times as great as the frictional engagement between arm 28 and lip section 22, before any bending couple is imposed upon bends 25.

In fabricating the tape links, the hinge loops are initially formed with a greater spread between arms 26 and 28 than in the final closed form of the loops, so that the arms 28 will be sprung inwardly when they are forced behind the lip sections 22, and will thereafter exert resilient compressive engagement with lip sections 22.

It will be apparent that the continuous bends 24 and 27 between lip sections 22 and 23, and between lip section 22 and body portion 9 (or 9'), extending continuously throughout the width of the link, may be given adequate strength to resist deformation under the tension applied thereto by the suspension of the links one by the other, and that the bends 25, which collectively have only a fraction of the full width of the link and correspondingly have only a fraction of the strength of bends 24, 27, have the ability to carry the loads imposed upon them, derived from the fact that said loads are applied closely adjacent to continuous edges of adjoining lip sections 23, plus the locking of the loops in closed form by the frictional engagement of arms 28 against lip sections 22. In the latter connection it will be noted that any tendency for the bends 25 to open up must necessarily be accompanied by a tendency for arms 28 to slide against the inner surfaces of lip sections 22, these surfaces being disposed substantially upon the circumference of the axis of bends 25 about which the loops would tend to pivot in the opening up process.

The links of each tape are supported in positions slightly inclined with reference to the general vertical plane of the tape, with alternate links inclined in directions opposite the intervening links. The degree of inclination of the links is determined by means for limiting the spreading movement of the links at hinges C'. Such means comprises stop fingers 30 constituting integral portions of links A projecting from the ends thereof which have the hinge loops 10, the fingers 30 being centered between loops 10, and projecting beyond the hinge axis to engage links A'. Hinges C' become locked against opening to fully spread positions of the adjacent links, as the result of pressure of link A' against finger 30 in one direction (as indicated by arrow 31) and pressure of trunnion 15' against loop arm 26 in the opposite direction (as indicated by arrow 32) at a point where the camming effect of trunnion 15' tending to ride upwardly against the inclined inner face of bend 25 under lateral force 32 is balanced against the tendency to ride downwardly on said inclined surface under the downward pull of the load imposed thereon. In some cases, the upper end of trunnion 15' may engage arm 26 at bend 29 to establish a final limit to the spreading movement. Each finger 30 defines a dihedral angle with respect to the extended plane of adjoining body portion 9. This dihedral angle is such as to cause adjacent links, in their fully

extended positions of hinging movement about the axis of hinge C', to assume a dihedral angle with respect to each other which determines a definite initial inward breaking of hinges C'.

This restriction of spreading movement of the links at hinge C' is utilized to correspondingly determine an initial breaking of the intervening hinges C. It will be apparent, upon reflection, that so long as alternate hinges are restricted in their opening movement so as to determine a definite dihedral angle between the links of said alternate hinges, the same dihedral angle must necessarily be present in the intervening hinges when the ladder is freely suspended, even though such intervening hinges do not have any corresponding means for limiting their opening movement. Furthermore, the movement limiting fingers 30 are disposed at the inner sides of the respective tapes and therefore concealed within the ladder structure, so that the outer sides of the respective tapes do not disclose any projecting fingers. This definitely improves the appearance of the ladder structure. Also, it makes it possible to form, in links A', the integral loops 11 at the respective positions occupied by fingers 30 in links A.

The hinge loops 10, 10' have a cross sectional shape which approximates both the cylindrical and the triangular, lying intermediate the two. It may best be described as a "heart shape." It is characterized by the curvature of arms 26 and 28 on a longer radius than that of the approximated cylinder of the same diameter, and the curvature of the connecting bends 25 and 29 on a shorter radius than the radius of such approximated cylinder. The radii of the arms 26, 28 may be such as to locate the centers thereof approximately at the centers of connecting bends 25 and 24, so that in the folding of the hinges, trunnions 15, 15' may consecutively pivot at approximately the centers of bends 25 and 24 with the edges of trunnions 15 opposite the pivoting edges travelling with roughly uniform clearance from the inner walls of arms 28, 26 respectively. For example, the folding of hinge C may be visualized as a series of pivotal movements wherein the trunnions first pivot at their inner edges upon bends 25, with their outer edges travelling along the inner walls of arms 28, and swinging toward lip section 23 until they have contacted the latter, and then pivot at their outer edge in bends 24 while their inner edges swing arcuately along the inner walls of arms 26.

This approximately triangular shape of the loops has several advantages. The bends 25, of sharper radius than that of the cylinder approximated by the loop structure, more accurately locate the trunnions supported therein, than in a strictly cylindrical hinge loop. Any engagement of bends 29 by the upper edge of trunnion 15' will, owing to the angle of engagement, result more in an upward component of force tending to press arm 28 into even more tight frictional engagement with lip section 22, than the lateral pressure tending to open up the loop. The broad curvature of arm 28 provides a greater area of frictional engagement with lip section 22 than would be attained by a surface of the cylinder approximated by the loop. All of these characteristics contribute to the much greater capacity for resisting the forces tending to open up the loops, in the present structure as compared to prior devices of this general type.

The restriction of the opening movement of the links is such that the axes of hinges C' will be

displaced appreciably inwardly from the axes of the hinges C, in the freely suspended ladder structure. Consequently, as the blind is raised by lifting force applied to the bottom slats, successive pairs of links A', A will be folded inwardly by the upward pressure, applied first to the lower links A' of such pair and transferred therefrom to the upper links through hinge C', while the next higher hinge C remains substantially immobilized by the weight of the slats applied thereto through its adjoining cross link B. With the two opposed hinges C' initially broken inwardly and their axes disposed inwardly of the axes of the hinges C above and below the same, the inward collapsing of the two pairs of links at their connecting hinges C' will be assured.

We claim:

1. A ladder structure for supporting a plurality of slats in a Venetian blind, comprising: a plurality of flat supporting cross links; and a pair of opposed articulated sheet metal tapes each including alternating first and second series links and a plurality of hinges joining said links end to end, with alternating outwardly breaking hinges linked together by said cross links and intervening inwardly breaking hinges adapted to be received between the slats when the blind is collapsed; said links each having at one end a pair of laterally spaced, aligned, integral sleeve-like hinge loops and at its other end a pair of aligned transversely extending slots spaced from said other end to define a pair of trunnions received in the respective hinge loops of the adjoining link, the hinge loops of said inwardly breaking hinges facing inwardly and being disposed largely on the inner side of the plane of their respective links and the hinge loops of the outwardly breaking hinges facing outwardly and being disposed largely on the outer side of the plane of their respective links; said hinge loops each including as an integral portion thereof, a lip of V-section channel form, extending continuously from side to side of the respective link and including a first lip section joined directly to the body of the link through a bend of obtuse angle form and a second lip section inclined in the opposite direction and joined to said first lip section by a substantially right angle bend, and said loops including separated portions each of generally U-shape joined to the free edge of said second lip section and having free end arms frictionally engaged against the inner wall of said first lip section, to lock said loops in closed positions in opposition to the tendency of the loops to open up under the pull of said trunnions.
2. A ladder structure as defined in claim 1, wherein each of said separated loop portions has an intermediate arm joined to said free end arm thereof, and a bend of sharper radius than the overall radius of the loop, joining said intermediate arm to the free edge of said second lip section, said last mentioned bend functioning as a stirrup to support the lower edge of the associated trunnion in closely spaced relation to said free edge of said second lip section so as to minimize the bending moment therein under the downward gravity pull of the load carried by said trunnion and thereby minimize the tendency of the loop to open under said pull.
3. A ladder structure as defined in claim 2, wherein said intermediate and free end arms are of outwardly bowed cross sectional shape, each having a radius greater than the said overall radius of the loop, and joined together by a bend of sharper radius than said overall radius, where-

by the loop is of substantially heart shape cross section.

4. A ladder structure as defined in claim 3, wherein the centers of curvature of said intermediate and free end arms are disposed approximately at the centers of said right angle bend joining said lip section and of said trunnion supporting bend, respectively.

5. A ladder structure for supporting a plurality of slats in a Venetian blind, comprising: a plurality of flat supporting cross links; and a pair of opposed articulated sheet metal tapes each including alternating first and second series links and a plurality of hinges joining said links end to end, with alternating outwardly breaking hinges linked together by said cross links and intervening inwardly breaking hinges adapted to be received between the slats when the blind is collapsed; said links each having at one end a pair of laterally spaced, aligned, integral sleeve-like hinge loops and at its other end a pair of aligned transversely extending slots spaced from said other end to define a pair of trunnions received in the respective hinge loops of the adjoining link, the hinge loops of said inwardly breaking hinges facing inwardly and being disposed largely on the inner side of the plane of their respective links and the hinge loops of the outwardly breaking hinges facing outwardly and being disposed largely on the outer side of the plane of their respective links; said hinge loops each including as an integral portion thereof, a lip of V-section channel form, extending continuously from side to side of the respective link and including a first lip section joined directly to the body of the link through a bend of obtuse angle form and a second lip section inclined in the opposite direction and joined to said first lip section by a substantially right angle bend, and said loops including separated portions each of generally U-shape joined to the free edge of said second lip section, and said hinge loops being of approximately triangular cross sectional shape, with said separated portions thereof having flattened intermediate and free end arms and bends of sharper radius than the overall radius of the loop, joining said arms and joining said intermediate arms to said free edges of said second lip section, respectively, said last mentioned bends functioning as stirrups to support the associated trunnions in close association with said free edge of the second lip section to minimize the bending moment therein under the gravity load imposed thereon by said trunnion.

6. A ladder structure for supporting a plurality of slats in a Venetian blind, comprising: a plurality of flat supporting cross links; and a pair of opposed articulated sheet metal tapes each including alternating first and second series links and a plurality of hinges joining said links end to end, with alternating outwardly breaking hinges linked together by said cross links and intervening inwardly breaking hinges adapted to be received between the slats when the blind is collapsed; said links each having at one end a pair of laterally spaced, aligned, integral sleeve-like hinge loops and at its other end a pair of aligned transversely extending slots spaced from said other end to define a pair of trunnions received in the respective hinge loops of the adjoining link, the hinge loops of said inwardly breaking hinges facing inwardly and being disposed largely on the inner side of the plane of their respective links and the hinge loops of the outwardly breaking hinges facing outwardly and being disposed largely on the outer side of the

plane of their respective links; said hinge loops each including as an integral portion thereof, a lip of V-section channel form, extending continuously from side to side of the respective link and including a first lip section joined directly to the body of the link through a bend of obtuse angle form and a second lip section inclined in the opposite direction and joined to said first lip section by a substantially right angle bend, and said loops including separated portions each of generally U-shape joined to the free edge of said second lip section, and said hinge loops being of approximately triangular cross sectional shape, with said separated portions thereof having flattened intermediate and free end arms and bends of sharper radius than the overall radius of the loop, joining said arms and joining said intermediate arms to said free edges of said second lip section, respectively, said last mentioned bends functioning as stirrups to support the associated trunnions in close association with said free edge of the second lip section to minimize the bending moment therein under the gravity load imposed thereon by said trunnion, and said free end arms being frictionally engaged against the inner wall of said first lip section to lock the loop against the tendency to open under said bending moment.

7. A ladder structure for supporting a plurality of slats in a Venetian blind, comprising: a plurality of supporting cross links; and a pair of opposed articulated sheet metal tapes each including alternating first and second series links and a plurality of hinges joining said links end to end, with alternating outwardly breaking hinges linked together by said cross links and intervening inwardly breaking hinges adapted to be received between the slats when the blind is collapsed; said links each having at one end a pair of laterally spaced, aligned, integral sleeve-like hinge loops and at its other end a pair of aligned transversely extending slots spaced from said other end to define a pair of trunnions received in the respective hinge loops of the adjoining link, said hinge loops each including as an integral portion thereof, a lip of V-section channel form, extending continuously from side to side of the respective link and including a first lip section joined directly to the body of the link through a bend of obtuse angle form and a second lip section inclined in the opposite direction and joined to said first lip section by a substantially right angle bend, and said loops including separated portions each of generally U-shape joined to the free edge of said second lip section and having free end arms frictionally engaged against the inner wall of said first lip section, to lock said loops in closed positions in opposition to the tendency of the loops to open up under the pull of said trunnions.

8. A ladder structure for supporting a plurality of slats in a Venetian blind, comprising: a plurality of supporting cross links; and a pair of opposed articulated sheet metal tapes each including alternating first and second series links and a plurality of hinges joining said links end to end, said links each having at one end a pair of laterally spaced, aligned, integral sleeve-like hinge loops and at its other end a pair of aligned transversely extending slots spaced from said other end to define a pair of trunnions received in the respective hinge loops of the adjoining link, said hinge loops each including as an integral portion thereof, a lip of V-section channel form, extending continuously from side to side of the respective link and including a first

lip section joined directly to the body of the link through a bend of obtuse angle form and a second lip section inclined in the opposite direction and joined to said first lip section by a substantially right angle bend, and said loops including separated portions each of generally U-shape joined to the free edge of said second lip section and having free end arms frictionally engaged against the inner wall of said first lip section, to lock said loops in closed positions in opposition to the tendency of the loops to open up under the pull of said trunnions.

9. A ladder structure for supporting a plurality of slats in a Venetian blind, comprising: a plurality of supporting cross links; and a pair of opposed articulated sheet metal tapes each including alternating first and second series links and a plurality of hinges joining said links end to end, with alternating outwardly breaking hinges linked together by said cross links and intervening inwardly breaking hinges adapted to be received between the slats when the blind is collapsed; said links each having at one end a pair of laterally spaced, aligned, integral sleeve-like hinge loops and at its other end a pair of aligned transversely extending slots spaced from said other end to define a pair of trunnions received in the respective hinge loops of the adjoining link, said hinge loops each including as an integral portion thereof, a lip of V-section channel form, including a first lip section joined directly to the body of the link through a bend, and a second lip section inclined in the opposite direction and joined to said first lip section by a bend, and said loops including separated portions each of generally U-shape joined to the free edge of said second lip section and having free end arms frictionally engaged against the inner wall of said first lip section, to lock said loops in closed positions in opposition to the tendency of the loops to open up under the pull of said trunnions.

10. A ladder structure for supporting a plurality of slats in a Venetian blind, comprising: a plurality of supporting cross links; and a pair of opposed articulated sheet metal tapes each including alternating first and second series links and a plurality of hinges joining said links end to end, said links each having at one end a pair of laterally spaced, aligned, integral sleeve-like hinge loops and at its other end a pair of aligned transversely extending slots spaced from said other end to define a pair of trunnions received in the respective hinge loops of the adjoining link, said hinge loops each including as an integral portion thereof, a lip of V-section channel

form, including a first lip section joined directly to the body of the link through a bend and a second lip section inclined in the opposite direction and joined to said first lip section by a bend, and said loops including separated portions each of generally U-shape joined to the free edge of said second lip section and having free end arms frictionally engaged against the inner wall of said first lip section, to lock said loops in closed positions in opposition to the tendency of the loops to open up under the pull of said trunnions.

11. A ladder structure as defined in claim 10, wherein each of said separated loop portions has an intermediate arm joined to said free end arm thereof, and a bend of sharper radius than the overall radius of the loop, joining said intermediate arm to the free edge of said second lip section, said last mentioned bend functioning as a stirrup to support the lower edge of the associated trunnion in closely spaced relation to said free edge of said second lip section so as to minimize the bending moment therein under the downward gravity pull of the load carried by said trunnion and thereby minimize the tendency of the loop to open under said pull.

12. A ladder structure as defined in claim 11, wherein said intermediate and free end arms are of outwardly bowed cross sectional shape, each having a radius greater than the said overall radius of the loop, and joined together by a bend of sharper radius than said overall radius, whereby the loop is of substantially heart shape cross section.

13. A ladder structure as defined in claim 12, wherein the centers of curvature of said intermediate and free end arms are disposed approximately at the centers of said right angle bend joining said lip section and of said trunnion supporting bend, respectively.

14. A ladder structure as defined in claim 10, wherein the links of one series have integral stop fingers on the ends thereof which have said hinge loops, said fingers projecting beyond the hinge axis to engage the adjacent link of said other series.
